SUSPENSORY BUCKLE

James Vincenzo Amendola, Kenosha, Wis.

Application January 22, 1941, Serial No. 375,506

3 Claims. (Cl. 24—73)

This invention relates to buckles for general surgical and other uses, and it is particularly valuable for use in the attachment of suspensories to the body of a person for various purposes, and particularly for the conventional suspensory, and has for an object to present a simplified connection means by which the several straps and elastic of such devices may be connected in a manner to afford a maximum comfort to the wearer, as well as eliminating many of the disadvantages involved in the use of the conventional prior fastening members.

As is well known, at the present time, a suspensory ordinarily includes a waistband, usually of elastic material, attached permanently at one end to a non-elastic strap base or pad portion from which the conventional suspensory sack is suspended, the sack being permanently attached thereto. On the base piece there are ordinarily required a buckle for connecting the end of the waist-band, and respective buckles for connecting the ends of the leg straps, the leg straps being permanently attached to the sack at the rear part of the latter, all of these buckles requiring separate operations of attachment to the base piece. It is therefore an important aim of my invention to eliminate the separate operations of attachment in order to attain fastening means for the several straps in such suspensories, as well as adapting my device for use in various other suspensories.

A further important aim of the invention, is to present a buckle device which combines several functions and capabilities of attachment not found in the conventional buckle, and especially suiting it to surgical uses, and other peculiar situations where a number of straps are required to be connected, and especially where they must lead to the buckle in an angular relation to each other.

Additional objects, advantages and features of invention reside in the construction, arrangement and combination of parts involved in the embodiment of the invention, as will be more readily understood from the following description and accompanying drawing, wherein

Figure 1 is a view of a buckle embodying my invention attached to a strap and base piece for one of its possible uses.

Figure 2 is a perspective view of the same buckle without any connected parts.

Figure 3 is a plan of a modification of the buckle.

Figure 4 is a plan of a double buckle.

Figure 5 is a similar view of another form of the double buckle.

Figure 6 is a view of a buckle embodying the features of the last mentioned device, further modified to adapt it to use in suspensory devices.

Figure 7 is a perspective view of the buckle of Figure 3.

Figure 8 is a plan view of a buckle constituting a further modification of the invention.

Figure 9 is an edge view thereof.

There is illustrated in Figure 1, a buckle consisting of a double prong wire frame piece 10, substantially U-shaped in general form, but having its bight portion 11 broadened so as to form an approximately rectangular frame piece having a bottom pivot bar 12, by which the buckle may be attached to a strap 13 or the like, as shown in Figure 1. In the present instance, the strap is looped around the bar 12 and secured to the base pad 14 which underlies the whole buckle, as shown. The attachment of the loop to the bar 12 in this instance at the same time secures the device upon the supporting pad or base piece 14. From the bar 12 two side portions 15 extend at right angles, a short distance, the wire being then bent inwardly at a sharp angle parallel to the bar 12, forming shoulder bars 16, and the ends of the wire at the inner parts of these bars 16 are bent outwardly at a sharp right angle and extended in parallel relation, to form prongs 17. A cross bail plate 18 is provided, comprising two arms 19 having their ends engaged pivotally around respective shoulder bars 16, these arms being divergently outward so as to leave a broad space beside the prongs 17, and the plate is formed with a transverse edge 20 adapted to lie under the point of the prong 17, as shown in Figure 1. The body of the plate 18 outwardly of the edge 20 is somewhat triangular in shape, providing an outer transverse edge 21, which is disposed at an angle to the edge 20, this angle in the present instance being in the neighborhood of twenty degrees or more, and having suitable ears 22 formed on its edge, in which there is pivoted a wire frame device, 10', similar in shape to the one 10, first described, and having elements corresponding to those described in the member 10, but being approximately one-half the size. Upon this prong frame 10', there is pivoted across bail member 25, having arms 26 at each side similar to those 19, before described, and having a transverse bar 27 located so as to lie under the points 17' of the piece 10', as shown in Figure 1.

In the broader end of the plate 18, which may be slightly extended beyond the adjacent arm 19

for the purposes desired, there is formed a large opening 28, adapted to receive a tape therethrough, or the like, and pivoted upon the plate 18 inwardly of this opening, there is a spurred keeper tongue 29, which is pivoted to swing in a plane parallel with and close against the plate 18, so that the spurs 30 thereof will extend slightly beyond the opening, and adapted to penetrate a plate or the like which is inserted through the opening, and to retain the same against withdrawal when inserted from the under side next the piece 14, and the end drawn outwardly a sufficient distance for the spurs 30 to engage therein.

In Figure 2, the device illustrated is identical with that shown in Figure 1, with the exception that instead of several ears 22, a single ear 31 is formed, engaged around the base bar 12' of the wire frame piece 10'.

In the use of this device, the band 13 may be body-encircling band or belt, according to the 20 suspension use of the article, and the band 13 may be either a shoulder strap or a waist-band. In case the suspension is used for supporting an injured arm or hand, the band 13 would ordinarily be used as a shoulder strap, and a tape 25 extended from the opening 28, or bandage element similarly attached, or could be extended around the body of the wearer, and attached to the arm to be supported, and continued therefrom to the buckle element at 10', where the end of the tape or other supporting means could be connected. By proper adjustment of the band 13 an injured member would thus be supported in close relation to the body of the wearer.

In such conventional use, the base piece 14 is 35 adjusted at the front of the abdomen of the wearer, while the band 13 is passed around the waist and its ends inserted under the bail 18 and forced upwardly under the edge 20 and outwardly from the device, the points 17 being then pressed against the extended end portion, so that when the latter is released, the tension on the belt will draw the end portion backwardly until it is checked by the spurs or prongs 17, the latter penetrating the band and being drawn by the band downwardly toward the bar 18 until the parts rest thereagainst. The remaining extremity of the belt may then be disposed of, or retained in any conventional way, familiar in such devices. A leg strap from the suspensory device, after passing rearwardly therefrom under the crotch of the wearer, may be brought forwardly around the leg of the wearer and its end secured in the supplementary diagonally disposed buckle 10'. By reason of the arrangement of this buckle on the diagonal edge 21, the direction of the leg strap is accommodated, these leg straps usually extending upwardly and inwardly toward the extremity of the leg strap, as is well known. If desired, the opening 28 may be utilized for attaching a tape extended upwardly from a suspensory bag or the like, so that the latter may be detachably supported by my buckle, instead of being permanently attached to the support piece 14, which would be the conventional practice.

For such use as last described, my buckle is of peculiar value, enhancing cleanliness of suspensories, by enabling their more ready laundering independently of the belt and strap device, as well as allowing the latter to be renewed and replaced readily, or laundered separately, from the suspensory bag when necessary.

In Figure 3, there is illustrated a further improvement in buckle construction, in which a frame piece 40 is provided, of simple rectangular

form, being adapted to be stamped of sheet metal with a single opening therethrough, although other features of my invention above described may be added thereto, if desired. The frame includes 5 side bars 41, a bail bar 42, and a pivot bar 43, constituting the base of the buckle. Some of the material of which the frame is formed, struck from the opening 44 of the device is curved toward one side of the frame and recurved, so as to form a pivot sleeve 45 which is engaged around the base bar 12-a of a wire pin 10-a, corresponding to that numbered 10 in Figures 1 and 2, and of identical form, the two points 17' being adapted to swing against the bail bar 42, while the lateral bight 46 formed by the parts 15' and 16' corresponding to the parts 15 and 16 before described, are arranged to clear the openings 44, so as to permit a wide strap to lie therein, with its edges close to the side members 43 of the frame 40. This device has the same advantage as the first described article in that the pin piece is so arranged that a strap may pass therethrough in the clear, with its full width lying flat. In the device of Figure 3, the butt end of a belt may be passed upwardly through the bight portion 46 as viewed in Figure 3, and inserted then downwardly over the points and through the frame 40, the points being below the frame in this view, and when the points are inserted 30 through the end portion, this will serve as a fastening for the belt and buckle, while the other end may be then also inserted downwardly through the frame 40, and then drawn backwardly and with the points inserted therethrough will be thereby secured adjustably. The butt end of the belt beyond the point of engagement of the points 17' may be inserted upwardly and through the bight 46 and extended outwardly over the pivot sleeve 45 under the body portion of the belt, to make a neat appearance.

In Figure 5, a buckle frame 50 is illustrated, consisting of side bars 51, a base bar and pivot sleeve 52 and successively spaced therefrom three cross bars 53, 54, and 55, the latter being the outermost. While these are shown uniformly spaced, the spacing may be varied to meet various requirements, as will be understood. Pivoted in the sleeve bar 52, there is a pin frame member 56, generally resembling the one 10, first described, except that the points 57 are much longer, the lateral bight portions 58 being substantially of the same size as the corresponding parts in the members 10 and 10-a. The bars 52 and 53 are so spaced that the bight portion 45 of the pin member 56 aligns with the frame part, and affording an opening 59 through which the ends of a belt or other band or strap may be inserted as may be required. The device as thus described has a central slot 60, and an outer slot 61, through which respective bands, straps or belt ends may be passed for securement by the points 57, as will be understood.

In the use of this device for a conventional suspensory, the conventional waist-band or belt may be connected either to the bar 52 as illustrated in Figure 1, at 13, or may be secured by being passed upwardly through the opening or slot 59, and downwardly through the slot 60, where the points 57 are passed therethrough, and the band material drawn backwardly until stopped by the engagement of the pin across the bars 54 and 55, as well as the bar 51. This affords a great deal of support for the pin portions engaged through the band material, and greatly strengthens the anchorage of the band. The

extremity of the band so engaged may then be recurved and passed outwardly through the slot 59 and over the bar 52, where it will be held and concealed under the body portion of the strap. The other end of the strap may then be secured by insertion through the slot 60 or the slot 61, and the points 57 engaged therethrough to retain it in adjusted positions. After engagement of the other end of the waist-band or belt in the slot 60, a leg strap may be secured in the slot 61 by being passed downwardly therethrough, and points 57 engaged through the inserted part of the leg strap after the latter has been adjusted to proper position.

In the last described form of the buckle, the points 57 are so supported by the bars 53, 54 and 55 that the points 57, made of comparatively fine wire, are enabled to sustain the secured strap ends with a minimum of liability of bending or dislodgement, enabling a comparatively light weight buckle structure to perform heavy service when required.

In Figure 6 there is illustrated a further development of the buckle shown in Figure 5, adapting it particularly to use with the conventional suspensory bag, and waist-band and leg strap. In this instance the frame 62 corresponding to the frame 50 before described, is formed with a considerably elongated side bar 65, corresponding to the side bar 51 in the last form of the device, while the opposite side bar 64 is of the same length as the side bar 51, before described. The width of the buckle may be the same as in the device of Figure 5. The frame 62 is formed with a base bar 65 which may be the same as the bar 52, last described, and the second bar 66 the same as the bar 53 before described. A third bar 67, however, is formed substantially in the shape of the bail bar 16 of the first described buckle, being considerably broadened at the right hand side, while the left hand end is of substantially the same width as the bar 54. An outer or fourth bar 68 is formed next the outer ends of the side bars 63 and 64, this bar being parallel to the outer edge 69 of the triangular bar 67. Transverse slots 70 and 71 are thus formed between the bars 65, 66 and 67, which are simple rectangular ones corresponding to those 59 and 60 before described, and a diagonal slot 72 is formed between the bars 67 and 68, the transverse edges of the slot 72 being parallel and the slot having the same width as the others between the bars 67 and 68, as well as between the bars 63 and 64. A pin piece 73 is provided on the buckle, having a base the same as that of the pin members 57, and as shown in Figures 1 to 3, inclusive, and Figure 7, this base portion including two bights 78' which aline with end members around the slot 70, as understood. The base portions of the points 74 of this device are extended as before, at right angles to the pivot axis and with respect to the bar 66, but immediately beyond the slot 51 they are bent diagonally, as at 75, so as to cross the slot 72 also at right angles to the latter slot. This device may be utilized in the same way as described for using the device of Figure 5, but it has the advantage of enabling a leg strap to extend therefrom with less likelihood of twisting, and will give the strap a better direction adjacent the buckle, as well as equalizing the strain between the strap and the respective pin members 74.

In Figure 8 there is shown a three bar buckle frame 80, of rectangular form in the present in-

stance, although it may be varied in accordance with the previous disclosures herein, if desired. It consists, in the present instance, of curved side bars 81, a base bar 82, a middle bar 83, to permit fastening and an outer bar 84, the latter three being cross bars, and arranged parallel to each other, so as to form a base slot 85, and an outer slot 86. A pin or prong member 87 is provided in this device which is in the same form as the pin or prong member 10—a described, and shown in Figures 3 and 7, and is pivoted on the base bar 82, in the same manner as the device of Figures 3 and 7, but has the additional advantage that by curving the side bars 81, the buckle may be more readily fastened and the outer point portions are better supported by the bars 83 and 84, so as to minimize liability of deforming of the pin or prong member and its points.

In Figure 4 there is shown a device which in effect constitutes a double buckle frame 90 having the elements of the buckle of Figure 3 duplicated at each end, but with a single control pivot cross bar 91, in which the base portion of two pin members 92 are commonly pivoted in the same manner that the single pin member of Figure 3 is pivoted. Outwardly of the central bar 91, there are intermediate pressure bars 92', and at each extremity of the frame 90 there are parallel pressure bars 93. These bars form inner slots 94 at each end of the buckle, and outer slots 95, as shown. The bight portions of the pin members 10—b, which correspond to the members 10 and 10—a before described, are alined with the slots 94, while their point portions 17—b are supported at their bases upon the bars 92', and their points upon the respective adjacent bars 93.

In the use of this device, a belt, band or strap 40 may have one end secured around the bar 91, while its other end may be engaged through one of the slots 95 and held by the pin point there-adjacent, while the other end of the buckle may be utilized to secure one or more other straps or bands, and particularly the end of a leg band of a suspensory, in which instance the device may be shaped to conform to the structure of Figure 6 at one end, so that a diagonally extending strap may be more readily connected thereto.

My invention utilizing the pin or tongue elements 10, 10—a, etc., as illustrated in all of the different forms of the invention has the advantage of enabling a strap to be engaged with my buckle without requiring it to be perforated or otherwise weakened centrally to permit it to pass around a prong, point or the like pivoted on the buckle, and also to permit the insertion of an outer extremity of a belt or the like, downwardly through the buckle, retaining all the advantages of a pivoted pin or prong device for positive anchorage of a strap end, while at the same time having the advantages of one-piece buckles in permitting the insertion of the loose strap end downwardly therethrough. It also attains the advantage of holding the loose strap end without requiring special enlargement of the buckle frame to extend beyond the pivot axis of the pivoted tongue or point, as in conventional buckles.

The invention as illustrated in Figure 1 and Figures 4 to 6, inclusive, and as otherwise described, has the advantages of providing a complete buckle assembly for a conventional suspensory, while attaining the elimination of numerous attaching operations required in conventional devices, while at the same time giving a

compact and convenient arrangement of the connecting means for the several bands and straps involved in such devices. The device shown in Figure 1 has all of the essentials for a complete suspensory bag mounting, a single leg strap being sufficient to anchor the lower part of the bag, as will be understood, for which reason only a single auxiliary buckle has been shown upon the main larger buckle bar 18. However, if desired, an additional small buckle, or a second leg strap may be mounted upon the device in the proper angle, if desired, this being thought to require no illustration.

While I have described my invention with great particularity, it will be appreciated and understood, as already indicated, that various modifications in the construction, arrangement and combination of parts, and substitutions of equivalents, may be made without departing from the spirit of the invention, as more particularly set forth in the appended claims.

I claim:

1. A buckle of the character described comprising an penetrating tongue element in the form of an open wire frame having a pivot bar and a pair of inwardly extended bars parallel thereto, said bars being bent at right angles defining a pair of penetrating tongue elements, a cross bail member pivoted on the bars laterally outward of the penetrating tongue elements and having a portion adapted to receive the penetrating tongue elements of the frame thereagainst, said cross bail member being broadened to form an inclined edge at its outer part beyond the point of contact of the penetrating tongue elements, and a

second buckle pivoted on said inclined edge, constructed for engagement with a strap end, as described.

5 2. The structure of claim 1 in which said broadened portion of the cross bail is provided with an opening therethrough, and a prong member swingably pivoted on the cross bail, adapted to swing across said opening in close relation thereto, and for penetration of a strap or the like inserted through said opening.

10 3. A buckle member comprising a penetrating tongue frame element bent to form a pivot bar and having outer point portions inset toward each other in parallel relation whereby to form laterally extending bars at respective sides, said tongue frame being formed of wire; a cross bail member stamped from sheet metal having respective arms formed for pivotal engagement around respective bars adjacent the bases of the points and including a flat cross bail member extended in a plane parallel with said bars whereby to present a transverse edge portion to receive the point portions thereagainst, said cross bail member having an inclined outer edge, a hinge knuckle formed thereon, a buckle pivoted on said knuckle and including a bail having a pressure bar inclined with respect to the inner side of said flat cross bail member, and said buckle having penetrating tongue elements thereon inclined with respect to the first named penetrating tongue elements and cooperable with the second named cross bail member as a pressure bar, for the purposes described.

JAMES VINCENZO AMENDOLA.
